UNITED STATES PATENT OFFICE

WALTER J. SKINNER, OF BLOOMFIELD, NEW JERSEY, ASSIGNOR TO VAN WICKLAND PRODUCTS CO., OF NEWARK, NEW JERSEY, A CORPORATION OF NEW JERSEY

HEATER UNIT FOR CATHODES OF VACUUM TUBES AND METHOD OF PRODUCING SAME

Application filed February 7, 1931. Serial No. 514,156.

This invention relates to heater units for the cathodes of vacuum tubes, and to a method of producing the same.

More particularly the invention provides 5 an improvement in heater units for cathode tubes in which the filament is given the form of a return helix, and aims to provide improved means for supporting and insulating such filaments. The particular means adopted 10 for carrying out the object in the preferred form consists of insulating collars through which the wires of the filament are threaded.

The invention also includes a method of 13 producing the improved heater unit.

While preferred forms of the invention are disclosed herein for purposes of illustration, it should be understood that various changes may be made in the structure or 20 method without departing from the spirit and scope of the invention as hereinafter set forth and claimed.

In the drawings:

Figure 1 is a vertical elevation partly in 25 section of a cathode structure including the improved heater unit.

Figure 2 is a vertical elevation of a heater unit before it is assembled in a cathode tube.

Figure 3 is a vertical elevation of a modified 30 form of heater unit.

Figure 4 is a vertical elevation of a further modified form of heater unit.

Figure 5 is a perspective view of one of the 35 insulating collars.

Figure 6 is an elevation showing a filament wire with collars threaded thereon preparatory to the winding operation.

Figure 7 is an elevation partly in section, showing the machine for carrying out the 40 winding operation.

Figure 8 is a view similar to Figure 6 but showing the relation of parts after the wire has been twisted.

Fig. 9 is a vertical elevation partly in section of a modification of the cathode structure.

Referring to the drawings more particularly, the tube 10 is the conventional cathode tube covered with an emissive coating 11 50 and provided with a tab 12 for connection

to a suitable conductor, as well understood in the art. The heating element 13 is connected to suitable conductors 14, and is supported and insulated both from itself and from the cathode 2 by collars 15 and 16, and by the central rod 17. The parts 15, 16 and 17 may be made of any suitable insulating material, such as magnesium oxide.

The collars 15 and 16 are formed with the central opening 18, as shown in Figure 5, 55 and with two side apertures 19 for passage of the filament wire.

In the process of forming the heater unit the filament wire is first bent back upon itself to the hairpin form illustrated in Figure 6, and the two free ends are then threaded through the side apertures 19 of the upper collar 15 and the lower collar 16 to the position indicated in Figure 6. This assembly 60 is then placed over the needle of the winding machine as shown in Figure 7.

The winding machine includes a suitable support 20 carrying a guide member 21. A sleeve 22 projects downwardly from the member 21 and is internally threaded for co-operation with a threaded sleeve 23, which is connected as by a set screw 24 to the shaft 25. The upper end of shaft 25 carries the needle 26 which projects upwardly through an opening in the guide 27. Suitable means 70 not shown is provided for rotating shaft 25.

After the preliminary filament assembly has been placed over the needle to the position of Figure 7, the operator grasps the lower collar 16 and holds it against movement. Shaft 25 is then rotated and this rotation together with the co-operative threads on 22 and 23 causes the needle to rotate and advance upwardly simultaneously. This operation is continued until substantially all of 80 the filament has been twisted, leaving the lower ends straight for attachment to the conductor 14. The filament assembly is now removed from the winding machine and is in the form shown in Figure 8, with the filament wire forming a double helix between the collars 15 and 16.

The insulating rod 17 is now inserted through the bores 18 to produce the heater assembly of Figure 2 and this heater assembly 100

is then inserted within the cathode tube to the final position of Figure 1. It will be clear that in this assembled position, the sleeves 15 and 16 together with the rod 17, 5 keep the two leads of the filament insulated and separated from each other. At the same time the collars 15 and 16 keep the filament spaced and insulated from the cathode tube. This method of insulating the filament is 10 much more positive than the use of insulated coating and serves to practically eliminate the possibilities of short-circuiting the filament during the process of manufacturing the vacuum tubes or during its subsequent use.

15 When the filament assembly is in the condition illustrated in Figure 8, a slight rotation of collar 16 relative to collar 15 will cause the opposite leads of the filament wire to contact with each other just above the collar 16. 20 If this filament assembly is inserted within the cathode tube without any rotating of the collar 16 relative to the collar 15, and these collars can be held against subsequent relative rotation, it is unnecessary to use a central insulating rod 17, as the collars 15 and 16 provide sufficient insulation and support for the filament. And while such a structure requires more accuracy in assembly than is at 25 present practical in commercial production, the present invention is broad enough to include it.

In the preferred form a complete central support rod extending through both collars is used as at 17 in Figure 2. This rod keeps 30 the coils from contacting in the manner just explained and holds the filament coil rigidly centered in the cathode tube. However a short section of insulating rod may be inserted through the lower collar 16 and into 35 the lowermost several coils of the filament, as at 17' in Figure 3, and such a section is sufficient to prevent the short-circuiting of the coils just above collar 16 due to relative rotation of collars 15 and 16.

40 It is possible by the method disclosed herein to place more than two collars on the filament, and while any desired number of the collars may be used, the preferred number is either two as in Figure 2, or three as illustrated in Figure 4, the third collar being placed at the center of the filament as an additional precaution against the center of the filament being knocked into contact with the cathode by excessive vibration or a heavy 45 blow from the outside. The multiple collar assembly of Figure 4 can, of course, be used without a central rod, as illustrated in that figure, or with a short rod 17' as in Figure 3, or with a rod 17 extending the full length of 50 the filament as in Figure 2.

A further modification is shown in Figure 5. In producing the filament assembly used in this form only the lower collar 16 is assembled on the wire before twisting, and after 55 twisting the assembly is like that shown in

Figure 8 but without the upper collar 15. This filament assembly is then inserted into the cathode tube 10, and a collar 28, which has a center bore large enough to accommodate the twisted filament, is placed in the upper end of the cathode tube and serves to insulate the upper end of the filament. Collar 28 may have a press fit in the cathode tube, or it may be retained in place by any other preferred means. A support rod 17 preferably extends through the filament for its entire length, although a short rod 17' may be used in the lower end only if desired.

60 It will be understood by one skilled in the art that the present invention provides an efficient and easily assembled means for insulating filaments of the coiled type without using insulating coatings on the filament.

I claim:

1. A device of the character described comprising a filament wire formed into a double helix, an insulating collar at each end of the helix, each collar being formed with a central aperture, a rod passing through the central aperture of each collar and through the central axis of the helix, each collar being formed with two side apertures spaced from the central aperture, the filament wire passing through both side apertures of each collar.

2. A device of the character described comprising an upper insulating collar formed with at least two apertures, a filament wire passing through one of the first-named apertures and being bent back upon itself beyond the collar and passing through the other of the first-named apertures, a lower insulating collar formed with a central aperture and two side apertures, each lead of the wire passing through one of said side apertures, the two leads of the wire between the collars being twisted into a double helix, and an insulating rod extending through said central aperture and through several turns of the helix adjacent to the lower collar.

3. A cathode assembly for vacuum tubes comprising a cathode tube, a pair of insulating collars, one of the collars being located within each end of the tube, each collar being formed with a central aperture and two side apertures spaced from the central aperture, a filament wire passing through both apertures of each collar, the portions of the wire lying between the collars being twisted into a double helix, and an insulating rod passing through the central aperture of each collar and through the central axis of the helix.

4. A cathode assembly for vacuum tubes comprising a cathode tube, an upper insulating collar located within the upper end of the tube and formed with two side apertures, a lower insulating collar located within the lower end of the tube and formed with a central aperture and two side apertures, a

filament wire passing through both side apertures of each collar, the portions of the wire lying between the collars being twisted into a double helix, and an insulating rod passing through the central aperture of the lower collar and through several turns of the helix adjacent to the lower collar.

5. The method which comprises providing a plurality of insulating collars, each of 10 which is formed with at least two apertures, bending a piece of filament wire into hairpin shape and threading the free ends of the wire through respective apertures in each collar, to a position in which the collars are 15 located close to each other at the bend of the wire, twisting one collar with respect to the other, and increasing the distance between the collars thereby twisting the wire into a double helix between the collars.
- 20 6. The method which comprises providing a pair of insulating collars, each of which is formed with a central aperture and with two side apertures, bending a piece of filament wire into hairpin shape and threading the free ends of the wire through respective side apertures in each collar to a position 25 in which the collars are located close to each other and near the bend of the wire, inserting a forked needle through the central apertures of the collars and into engagement with the bend of the wire, holding stationary the collar farthest from the bend of the wire, rotating the needle and moving its forked end away from the stationary collar, thereby 30 twisting the wire into a double helix between the collars, removing the needle, and inserting an insulating rod through the central aperture of each collar and through the central axis of the helix.
- 35 7. A cathode assembly for vacuum tubes comprising a cathode tube, a lower insulating collar located within the lower end of the tube and formed with a central aperture and two side apertures, an uncoated filament 40 wire passing through both side apertures, the portion of the wire above the lower collar being twisted into a return helix, and a collar insulating the upper end of the helix from the cathode tube.
- 45 8. A cathode assembly for vacuum tubes comprising a cathode tube, a lower insulating collar located within the lower end of the tube and formed with a central aperture and two side apertures, an uncoated filament 50 wire passing through both side apertures, the portion of the wire above the lower collar being twisted into a return helix, and an upper insulating collar located within the upper end of the cathode tube and formed 55 with a central aperture large enough to accommodate the helix, the helix extending into the aperture of the upper collar.
